UNITED STATES PATENT OFFICE.

HANS M. T. PETERS, OF NEW YORK, N. Y., ASSIGNOR TO KNY-SCHEERER CORPORATION OF AMERICA, OF NEW YORK, N. Y., A CORPORATION OF NEW YORK.

MECHANICAL HORSE.

Application filed June 8, 1925. Serial No. 35,549.

My invention relates to an improvement in a mechanical horse and the novelty consists in the adaptation and arrangement of parts as will be more fully hereinafter pointed out.

It has been definitely determined by the medical profession that horse-back riding is one of the best forms of exercise which man can take, but the expense of maintaining a stable and the inconvenience and difficulty in obtaining time and conditions proper for such riding have made it impossible for most people to enjoy this form of outdoor exercise.

My device takes up a small amount of space, can be utilized in any home where there is electric power and is always ready for use at any time and regardless of any weather conditions. Furthermore, it is inexpensive to maintain and does not require any change in costume and can therefore be utilized by the busy man where a horse would be entirely impractical.

Referring to the drawings Figure 1 is a side elevation of my complete device. Figure 2 is the same as Figure 1 with certain portions being uncovered and others being shown in section in order to show the interior mechanism. Figure 3 is the same as Figure 2 but with the operating parts in different positions. Figure 4 represents details of the compression spring.

In the drawings 10 is a base member to which is rigidly secured at 11 a standard 12 to which is rigidly secured at 13 a neck portion 14 terminating at its upper end in a head portion 15.

An electric motor 16 is adapted to be rigidly secured in position on said standard 12 and which is adapted to be connected in the usual manner to the source of power which is not shown herein. A shaft 17 is driven by said motor 16 and on the opposite end of said shaft 17 from said motor 16 is rigidly mounted a worm gear 18 which rotates with said shaft 17. A sub-frame member 19 is rigidly secured in the usual manner to the standard 12 and in this sub-frame 19 is mounted a shaft 20 directly over and crosswise of said worm gear 18, said shaft 20 being mounted in the sub-frame 19 with the usual bearings 21. A cut gear 22 is rigidly secured to said shaft 20 so as to rotate there-

with and mesh with worm gear 18. A pair of circular eccentric plates 23 are mounted over each end of the shaft 20 and keyed thereto so as to rotate therewith, being mounted in bearing clamp members 24 which are clamped together in the usual manner at 25. The upper halves of said clamp members 24 are rigidly secured to the front end of a saddle frame member 26 at 27 so that as the eccentric plates 23 rotate with the shaft 20 the front end of the saddle frame member 26 travels therewith.

A pair of rocker members 28 are loosely mounted over the shaft 20 so as to turn freely thereon and have short arms 29. The short arms 29 of the pair of rocker members 28 have a pair of connecting rods 30 loosely secured to the lower ends of said arms 29 so as to turn freely at 31. The connecting rods 30 are also connected at their other ends by a loose connection to a bell crank lever 32 which is pivoted at 33. Another connecting rod 34 is movably connected at its lower end at 35 to said bell crank lever 32 and at its upper end is movably connected at 36 to a lever 37 which is pivoted at 38 and has an operating lever and handle 39 rigidly secured thereto. Said operating lever 39 has a compression member 40 of usual construction adapted upon pressure to disengage a tongue member 41 from guideway slots 42 so as to operate said lever.

At the upper ends of the rocker members 28 is a connecting rod 43 movably secured thereto and the opposite end of said connecting rod 43 is connected to the upper ends of a pair of levers 44 at the point where they join and which at their lower ends are rigidly secured to a shaft 45 on which is also rigidly mounted a pair of wrist plates 46. A pair of T-shaped guide members 73 are also mounted on the shaft 45 so that they will rotate freely thereon and they have guideway slots 49 and 53 in the lower portion and 56 in the upper portion. To the upper ends of the wrist plates 46 are loosely connected a pair of link members 47, the lower ends of which are loosely connected to headed pin members 48 which are adapted to travel in the guideway slots 49. A second pair of link members 50 are loosely connected to the lower ends of said wrist plates 46 and these link members 50 are loosely con-

nected by means of headed pin members 51 to another pair of link members 52. The headed pin members 51 are adapted to slide in guideways 53 and the upper ends of said link members 52 being loosely connected by means of headed pin members 54 to links 55, said headed pin members 54 being adapted to slide in guideways 56 and the opposite ends of said links 55 being loosely connected 10 to center pins 57 of the eccentric plates 23.

A pair of compression spring members 58 are loosely connected to the headed pin members 51 at the lower ends and at the upper ends are connected at 59 to the saddle 15 frame member 26. A pair of motor speed control members 60 are secured at one end to the connecting levers 44 at 72 running over pulleys 61 and having spring members 62 at the lower ends. This control mechanism is adapted to make the necessary contacts in order to increase the speed as the controls 60 are pulled by the throwing of the connecting levers 44 as shown in Figure 2 and running down to low speed as shown in 25 Figure 3.

The spring compression member 58 has a plunger member 63 and a spiral spring 64, the movement being limited by pins 65.

A rubber tension member 66 is adapted to 30 loop over the headed pin members 48 and headed pin members 67 rigidly secured on each side of the standard 12. A saddle frame cover member 68 is adapted to be rigidly secured to the saddle frame member 26 35 and a saddle 69 of usual construction is adapted to be mounted over said cover member 68 as shown in Figure 1.

In Figure 1 is also shown a pair of reins 70 secured in the usual way at 71 to the 40 head member 15.

The operation of my device is as follows: The rider mounts the saddle 69 in the usual well known manner adjusting the stirrups to the length desired. The rider 45 thus being seated in the regular position for riding will then turn on the source of power, not shown, thereby setting the motor 16 in operation whereupon the shaft 17, the worm gear 18 and the cut gear 22, meshing with 50 said worm gear 18 and the shaft 20 will thereby be driven through the connections as described, whereby the pair of eccentric plates 23 will be rotated in their bearings 24 so that the saddle frame 26, which is rigidly secured at 27 to the bearings 24, will thereby be raised and lowered with the rotation of said eccentric plates 23.

In the low speed operation of my device, 60 which is shown in Figure 3, the handle 39 is in the lower position as shown in said figure and the connecting rod 34, bell crank lever 32 and connecting rods 30 are in the position shown whereby rockers 28 are pulled at 31 to the position shown with the 65 base members 29 extending towards the neck

14 of my device. This results in pushing connecting rods 43, levers 44 to the position shown in Figure 3 and shaft 45 turns with the turning of levers 44 whereby wrist plates 46 are turned thereby throwing headed pin members 51 and 48 to the position shown in Figure 3. This results in shifting the base of compression spring members 58 at 51 to the position shown in Figure 3 and the result of the operation of the shifting of these 70 various connecting links which are hooked up to the eccentric plates 23 whereby the course of rotation described by the saddle frame member 26 will be an ellipse the axis of which will be substantially in a vertical 75 plane. The position of the levers 44 in Figure 3 also releases the speed controls 60 so that the spring 62 will draw them down as released so as to effect the low speed of the operation of the motor 16.

As the driver desires to accelerate the speed of my device he will compress the compression member 40 thereby releasing the tongue member 41 from guideway slots 42 so that the handle 39 can be raised whereby 80 the motion will be transferred pushing down connecting rod 34, bell crank lever 32 and connecting rods 30 thereby pushing the rocker members 28 so that the foot portions 29 are in the positions shown in Figure 2. 85 This turning of the rocker members 28 pulls the connecting rods 43 and levers 44 to the positions shown in Figure 2 whereby shaft 45 is turned and wrist plates 46 so that headed pin members 51 and 48 are drawn to the inner ends of slots 53 and 49 whereby the link members 52 are pushed upwardly with the headed pin members 54 all of which motions will tilt the T-shaped guideway member 73 to the position shown in Figure 2. 90 This results in changing the bases 51 of compression spring members 58 as well as the other connecting links described so that the motion described by the saddle frame member 26 will be substantially an ellipse having an axis the plane of which is more nearly in the horizontal position. This operation of my device as shown in Figure 2 will cause the levers 44 to draw on the speed 95 control members 60 thereby effecting the increase of speed simultaneously with the change of motion of the saddle frame member 26 as described. The tension members 66 will, during these operations, draw down on the headed pin members 48 so as to always keep them in proper tension thereby preventing any unnecessary throw or slipping.

It is thus seen that the motions described by my device approximate the motions attained by a live horse which is being driven in horse-back riding as the low speed operation gives us a shorter and more nearly vertical throw of the saddle frame member 26 whereas the high speed gives us the longer 100 105 110 115 120 125 130

throw which is attained by a live horse on the road when being ridden by a horse-back rider.

I claim:

1. In a mechanical horse the combination of a standard supported on a base, motive means mounted on said standard, a saddle frame member mounted over said standard, means connecting said motive means with 5 said saddle frame member and adapted to oscillate the same and comprising a pair of circular eccentric plates keyed to a cross shaft driven through intermeshing gears by 70 a driving shaft from said motive means, circular bearings clamped over said circular eccentric plates and rigidly secured to said saddle member near the front end of same, and means for varying the scope of oscillation of said saddle member comprising a 75 pair of circular eccentric plates keyed to a cross shaft driven through intermeshing gears by 80 a driving shaft from said motive means, circular bearings clamped over said circular eccentric plates and rigidly secured to said saddle member near the front end of same, and means for varying the scope of oscillation of said saddle member comprising a 85 spring compression member secured to the rear of said saddle frame member and means for varying the position of the lower end of said spring compression member.
2. In a mechanical horse the combination of a standard supported on a base, motive means mounted on said standard, a saddle frame member mounted over said standard, means connecting said motive means with 90 said saddle frame member and adapted to oscillate the same and comprising a pair of circular eccentric plates keyed to a cross shaft driven through intermeshing gears by 95 a driving shaft from said motive means, circular bearings clamped over said circular eccentric plates and rigidly secured to said saddle member near the front end of same, and means for varying the scope of oscillation of said saddle member comprising a 100 spring compression member secured to the rear of said saddle frame member and means for varying the position of the lower end of said spring compression member consisting of a neck and head portion and a lever in said head controlling a series of links and rockers whereby the raising of said lever pushes the base of said spring compressor member to an 105 outer position.
3. In a mechanical horse the combination of a standard supported on a base, motive means mounted on said standard, a saddle frame member mounted over said standard, means connecting said motive means with 110 said saddle frame member and adapted to oscillate the same and means for varying the scope of oscillation of said saddle frame member, comprising a spring compression member secured to the rear of said saddle frame member and means for varying the position of the lower end of said spring compression member, consisting of a neck and head portion and a lever in said head controlling a series of links and rockers whereby the raising of said lever pushes the base of said spring compressor member to an outer position and means for varying the speed of the motive means controlled by the movement of said head lever.
4. In a mechanical horse the combination of a standard supported on a base, motive means mounted on said standard, a saddle frame member mounted over said standard, 115 means connecting said motive means with said saddle frame member and adapted to oscillate the same, means for varying the scope and direction of oscillation of said saddle frame member comprising a pair of eccentric plates having bearings attached to said saddle frame member near the forward end of the same and a pair of spring compression members attached to said saddle frame member near the rear end of the same 120 and means for moving the base pivots of said spring compression members.
5. In a mechanical horse the combination of a standard supported on a base, motive means mounted on said standard, a saddle 125 frame member mounted over said standard, means connecting said motive means with said saddle frame member and adapted to oscillate the same and comprising a pair of circular eccentric plates keyed to a cross shaft driven through intermeshing gears by 130 a driving shaft from said motive means, circular bearings clamped over said circular eccentric plates and rigidly secured to said saddle member near the front end of same, and means for varying the position of the lower end of said spring compression member consisting of a neck and head portion and a lever in said head controlling a series of links and rockers whereby the raising of said lever pushes the base of said spring compressor member to an outer position.

- frame member mounted over said standard, means connecting said motive means with said saddle frame member and adapted to oscillate the same, means for varying the scope and direction of oscillation of said saddle frame member comprising a pair of eccentric plates having bearings attached to said saddle frame member near the forward end of the same and a pair of spring compression members attached to said saddle frame member near the rear end of the same and means for moving the base pivots of said spring compression members and means for varying the speed of such oscillation simultaneously with the variation of the scope and direction of the same.
8. In a mechanical horse the combination of a standard supported on a base, motive means mounted on said standard, a saddle frame member mounted over said standard,
- means connecting said motive means with said saddle frame member and adapted to oscillate the same, means for varying the scope and direction of oscillation of said saddle frame member comprising a pair of eccentric plates having bearings attached to said saddle frame member near the forward end of the same and a pair of spring compression members attached to said saddle frame member near the rear end of the same and means for moving the base pivots of said spring compression members, consisting of a tilting T-shaped guide member, links connected together from said eccentrics to said compression spring bases, a series of connecting rods and levers operated from the head of said horse controlling the changing of position of said links and pivots.

In testimony whereof I affix my signature.

HANS M. T. PETERS.
